UNITED STATES PATENT OFFICE.

MINOTT W. SEWALL, OF NEW YORK, N. Y., AND DAVID S. JACOBUS, OF JERSEY CITY, NEW JERSEY, ASSIGNORS TO THE BABCOCK & WILCOX COMPANY, OF BAYONNE, NEW JERSEY, A CORPORATION OF NEW JERSEY.

TILE FOR COVERING TUBES.

1,129,313.

Specification of Letters Patent. Patented Feb. 23, 1915.

Original application filed February 7, 1910, Serial No. 542,417. Divided and this application filed January 4, 1911. Serial No. 600,816.

To all whom it may concern:

Be it known that we, MINOTT W. SEWALL and DAVID S. JACOBUS, citizens of the United States, the former a resident of New York city, borough of Manhattan, in the county of New York and State of New York, and the latter a resident of Jersey City, in the county of Hudson and State of New Jersey, have invented certain new and useful

10 Improvements in Tiles for Covering Tubes, of which the following is a specification.

The present invention relates to a tile or brick designed more particularly as a covering for tubes of a water tube boiler, which 15 may be readily placed in position or removed therefrom without disturbing any other tile or brick, and to means for supporting the tiles on a tube.

20 The present application is a division of our application Serial Number 542,417, filed February 7, 1910, for a water tube boiler.

The invention will be understood by reference to the accompanying drawings in which—

25 Figure 1 is a top view of a portion of a roof of a boiler furnace to show the application of the invention as a tube covering; Fig. 2 a section on the plane of the line 2—2 of Fig. 1 on an enlarged scale; 30 Fig. 3 a section on the plane of the line 3—3 of Fig. 1; and Fig. 4 a modification of the form shown in Fig. 2.

Similar reference numerals indicate similar parts in the several views.

35 In the use selected for illustration, the roof 1 is formed of tiles shown in Fig. 3, and at the left-hand end of Fig. 1. These tiles have a lower face 2 struck on an arc, the center of which is in a vertical line 3 passing through the center of the corresponding tube 4, the center being such that the intersection of the arcs of two adjacent tiles will be above the horizontal center line 5 of the tubes. Above the point of intersection of the two arcs 2 the abutting faces are in a vertical plane. This position of the center gives such a form to the tile that when it is rotated upwardly about the tube center the tile will immediately free itself 45 from the adjacent tile and so permit of its rotation through a sufficient arc to remove it from its place without disturbing any other portion of the roof. These tiles of

Fig. 3, when supported on the tubes 4, break joint, as shown in Fig. 1, so that 55 the removal of one tile does not permit its companion to fall. A clearance is provided by cutting away the upper edge of the tile at 6 to permit of the rotation of the tile a sufficient distance to effect its 60 removal.

The tile shown in Fig. 2 and at the right-hand end of the tubes in Fig. 1, is slightly less than semicircular in section to allow a clearance between two tiles of a pair. They 65 may be made of any convenient length. On the inner face is a channel 7 formed by a locking rib 8 extending longitudinally thereof along one edge. Said rib projects inwardly beyond the face of the tile to 70 adapt the latter to the reception of a lug or lugs 9 on a locking member in the form of a loose metal plate 10 resting on the tube. When the metal plate is placed in proper position on the upper side of the 75 tube and the two tiles forming a pair are assembled with, and supported by, said plate, all are maintained in position for service as shown at the right-hand side of Fig. 1. In removing a tile, it is necessary 80 to take both of a pair off at the same time, and this can be readily done by grasping the tiles and separating the lower edges 11, a clearance between the upper edges of the tiles permitting them to move toward each 85 other a sufficient distance to be lifted free of the tube.

In the form shown in Fig. 2, the tiles are eccentric with the tubes by reason of the rib 8 extending beyond the inner face 90 of the tile. In the form shown in Fig. 4, the said rib is less than the thickness of the tile so that when it engages the lug or lugs 9 the tile will be concentric with the tube. 95

The invention is capable of general application to tubes of all kinds where a readily removable cover is necessary. We do not, therefore, confine ourselves to the particular use illustrated and described. 100

What we claim and desire to secure by Letters Patent of the United States is:—

1. A tile construction for the purpose described comprising tiles having substantially semi-circular inner faces and a locking rib, a tube, and means on said tube co- 105

operating with the ribs of a pair of said tiles to hold them in place about the tube.

2. A tile construction for the purpose described comprising tiles having substantially semi-circular inner faces and an internal locking rib along one edge thereof; a tube, and means on said tube coöperating with the ribs of a pair of tiles to hold them in place about the tube.

10 3. A tile construction for the purpose described comprising tiles having substantially semicircular inner faces and a locking rib, a tube, and a separate member resting on said tube, said member coöperating with the ribs of a pair of said tiles to hold them in place about the tube.

20 4. A tile construction for the purpose described comprising tiles having substantially semicircular inner faces and an internal locking rib, a tube, and a separate member resting on said tube, said member having lugs adapted to be engaged by said ribs to hold a pair of said tiles in place about the tube.

25 5. A tile construction for the purpose described comprising tiles having substantially semicircular inner faces and a locking rib, a tube, and a metal plate resting on said tube, said plate having projections adapted

to be engaged by said ribs to hold a pair of 30 said tiles in place about the tube.

6. A tile construction for the purpose described comprising tiles having substantially semicircular inner faces and a locking rib, a tube, and a separate member resting on said tube, said member coöperating with the ribs of a pair of said tiles to hold them in place about the tube, said tiles being formed with a clearance between their upper edges to permit of the simultaneous removal of the 40 tiles of a given pair.

7. The combination of a tubular supporting girder, a saddle fitting over said girder and channeled on its upper side, mutually matching blocks of refractory material recessed to embrace the girder and fit the channeled saddle, inclosing the girder and suspended by the girder, and means to maintain cooling circulation in the tubular girder.

45 In testimony whereof we have hereunto signed our names in the presence of two subscribing witnesses.

MINOTT W. SEWALL
DAVID S. JACOBUS.
